(12) **United States Design Patent** (10) **Patent No.:** **US D794,031 S**
You et al. (45) **Date of Patent:** **** Aug. 8, 2017**

(54) **MEMORY CARD SOCKET**

(71) Applicant: **Molex, LLC**, Lisle, IL (US)

(72) Inventors: **In Ho You**, Ansan (KR); **Sung Hyuk Chu**, Ansan (KR)

(73) Assignee: **Molex, LLC**, Lisle, IL (US)

(**) Term: **15 Years**

(21) Appl. No.: **29/548,536**

(22) Filed: **Dec. 15, 2015**

(30) **Foreign Application Priority Data**

Nov. 3, 2015 (KR) 30-2015-0055360

(51) **LOC (10) Cl.** **14-02**
